UNITED STATES PATENT OFFICE.

FREDERICK A. SCHOSOW, OF DETROIT, MICHIGAN.

SHAMPOO-SPRAY.

1,256,600.

Specification of Letters Patent. Patented Feb. 19, 1918.

Application filed December 26, 1917. Serial No. 208,728.

To all whom it may concern:

Be it known that I, FREDERICK A. SCHOSOW, citizen of the United States, residing at Detroit, county of Wayne, State of Michigan, have invented a certain new and useful Improvement in Shampoo-Sprays, and declare the following to be a full, clear, and exact description of the same, such as will enable others skilled in the art to which it pertains to make and use the same, reference being had to the accompanying drawings, which form a part of this specification.

My invention relates to a combined shampoo spray and bath tub or lavatory fixture shown in the accompanying drawings and more particularly described in the following specifications and claims.

One of the objects of this invention is to provide a device in which water may be discharged from either the bath tub or lavatory fixture,—or from the shampoo spray as desired:—the construction being such that the shampoo spray may be at all times connected with the bath or lavatory fixture without interfering with the operation of either, or it may be disconnected therefrom when not in use if desired.

Another object of the invention is to relieve the rubber tubing, connecting the bath tub or lavatory fixture proper with the valve controlling the shampoo spray, of the pressure of the water following the closure of the shampoo valve.

Another object is to provide means adjustable in accordance with the water pressure, for governing the operation of the bath tub, or lavatory relief valve upon closing the shampoo spray valve.

Another feature of the invention is that the temperature of the water may be determined and if necessary regulated, prior to the discharge of water through the shampoo spray.

With the foregoing and other objects in view which will appear as the description proceeds, the invention resides in the combination and arrangement of parts and in the details of construction hereinafter described and claimed, it being understood that changes may be made in the precise embodiment of the invention herein disclosed without departing from the scope of this invention.

In the accompanying drawings, Figure 1 is a vertical cross-sectional view

through a bath tub fixture, and a shampoo spray and controlling valve connected therewith.

Fig. 2 is a horizontal cross-sectional view through the bath tub fixture and the usual hot and cold water connections.

Fig. 3 is a front elevation of the bath tub fixture and hot and cold water connections, with parts broken away.

Fig. 4 is a plan view of the perforated disk carried by the stem of the valve controlling the discharge of water to the tub, fitted with one or more screws for regulating the water pressure.

Referring now to the letters of reference placed upon the drawings, A, B, denote respectively the hot and cold water inlet pipes under control of valves A', B'. C, indicates a T connecting the tail pieces of the respective valves with the fitting D.

E, denotes a valve controlling the discharge of water through the outlet D', into the tub (not shown).

The valve E, is mounted on a stem E', which carries also a disk E², of relatively larger diameter than the valve and spaced therefrom that the water entering the fixture may flow between the valve and disk. E³, are perforations in the disk for the passage of water and E⁴, are screws which may be used to close one or more of the perforations to secure a proper balance of pressure.

D², is a cap screwed into the lower end of the fitting D, having a projecting nipple to receive the end of a piece of rubber tubing F. G, denotes a valve casing connected to the opposite end of the tubing F, fitted with a spray nozzle G'. G², indicates a spring-seated valve having a stem projecting through the wall of the casing and fitted with a knob G³, for manually operating the valve. D³, indicates a closure cap for the top of the fitting D, recessed to receive and guide the cap-screw E², carried on the end of the valve stem E'.

Having indicated the several parts by reference letters, the construction and operation of the device will be readily understood.

Upon manually depressing the knob G³, carried by the stem of the spring seated valve G², water will flow past the valve G², and out through the shampoo nozzle G'. Owing to the relatively greater area of the perforated disk E², to the valve E, (the perforations serving for the passage of wa-

ter),—the water pressure on the disk E², forces it downward closing the valve E. Thus all the water passes through the perforations in the disk and out through the 5 shampoo spray nozzle G'.

Upon releasing the valve G², the controlling spring forces it to its seat thereby cutting off the discharge of water at the spray nozzle G'.

10 The water pressure being now equalized on both faces of the disk E², the valve E, is forced upward the water being free to discharge through the outlet D', into the tub.

15 One or more screws E⁴, fitted to the perforations in the disk E², are employed to close one or more openings in the disk, in order that a proper balance of pressure may be obtained. Thus should the back-pressure 20 tend to open the valve E, while the valve G², controlling the spray nozzle is open, another opening in the disk E², may be closed:—whereas should the volume be too small to operate the shampoo spray a 25 screw may be removed from the disk.

Having thus described my invention what I claim is:

1. In a device of the character described, a casing adapted to receive water from a 30 source of supply and provided with two discharge outlets for the water, a valve adapted to close one of said outlets, a disk spaced from the valve of relatively larger diameter than the valve and adapted to reciprocate therewith, a nozzle connected with the other discharge outlet, and a valve controlling the delivery of water through the latter, whereby upon opening the valve controlling the passage of water through the nozzle, the 35 pressure of the water upon the disk will serve to force the first named valve to its seat, or, upon closing the nozzle the pressure of the water upon the first named valve will force it from its seat that the water 40 may be discharged through the other outlet.

2. In a device of the character described,

a casing adapted to receive water from a source of supply and provided with two discharge outlets for the water, a valve adapted to close one of said outlets, a stem secured to said valve, a perforated disk, adapted to reciprocate within the casing, secured to the stem in spaced relation to the valve and of relatively larger diameter than the latter, 55 a spray nozzle, means connecting the spray nozzle with the other outlet of the fitting, and a valve controlling the discharge of water through the spray nozzle.

3. In a device of the character described, a casing adapted for connection with a hot and cold water supply system having two independently arranged discharge outlets for water, a valve adapted to close one of said outlets, a stem secured to said valve, a 60 perforated disk secured to the stem in spaced relation to the valve and relatively larger in diameter than the latter, removable means for closing one or more of the perforations in said disk, a spray nozzle, a 65 flexible connection between the spray nozzle and the other water outlet of the fitting, and a manually operated valve for controlling the discharge of the water through the spray nozzle. 75

4. In a device of the character described, a casing adapted for connection with a hot and cold water system, having two independently arranged discharge outlets for water, a spray nozzle connected with one of 80 said outlets, a manually operated spring-seated valve for controlling the release of water through the spray nozzle, a valve fitted with a stem for controlling the discharge of water through the other outlet, 85 and a perforated disk secured to the stem of relatively larger diameter adapted to reciprocate with the valve within the casing.

In testimony whereof, I sign this specification in the presence of two witnesses.

FREDERICK A. SCHLOSSOW.
